UNITED STATES PATENT OFFICE.

JOSEF WEISER, OF VIENNA, AUSTRIA-HUNGARY.

OIL-RETORT.

1,127,951.

Specification of Letters Patent.

Patented Feb. 9, 1915.

Application filed October 6, 1911. Serial No. 653,262.

To all whom it may concern:

Be it known that I, JOSEF WEISER, chemical engineer, subject of the Emperor of Austria-Hungary, residing at Vienna, in the Empire of Austria-Hungary, have invented certain new and useful Improvements in Oil-Retorts, of which the following is a specification, reference being had therein to the accompanying drawing.

10 The usual method of distillation in the petroleum industry is as follows: Benzin and petroleum are distilled over in the petroleum stills in which a residue is left which is composed of a mixture of lubricating oil, paraffin and coke; this is distilled over in separate oil stills so long as no solid constituents become burnt onto the heating surface. The residue remaining in the oil stills is then introduced into the coking still 20 and there distilled to coke. Upon the completion of this distillation process the whole of the residue remaining in the still constitutes a solid porous mass, about 30 cm. in height which when the coking still hitherto employed is used, becomes firmly burnt onto the bottom of the still, and has to be removed by means of scraping and cutting tools. The distillation to coke is therefore a distillation to the point of complete desiccation which results in numerous disadvantages because it entails the burning of solid constituents onto the heating surfaces of the still. For this reason the treatment of the residues until they assume the form of coke 30 is regarded as unprofitable in most refineries.

The defects arising in carrying this process into practice are as follows: The burnt-on coke constitutes a very good insulation 40 to the transmission of heat. Consequently those parts of the heating surfaces onto which the coke has burnt, become incandescent and the iron is burnt through; the stills in which the distillation to coke is effected must be replaced after about 30 distillations, for the purpose of renewing the bottom of the boiler, for these reasons. As the deposit of the layer of coke insulates the heating surface and the heat supplied 50 from the furnace can only reach the interior of the still with difficulty, the distillation process is greatly impeded especially in that stage in which the last constituents which have a high boiling point are driven 55 out of the boiler. As a consequence of this

it is necessary to produce superheated furnace gases which pass off through the chimney, unutilized and cause waste of heating material. Owing to this relatively fierce heating the temperature at the surface of the still is much too high and these high temperatures give rise to undesirable decompositions entailing great loss of valuable hydrocarbons.

The elements which form the object of the present application and which are intended to obviate these defects, are broadly based upon the observation that the solid constituents are deposited mainly at the lowest parts of the still and that in the boilers hitherto employed the burning on of these solid constituents is due only to the fact that the place at which the solid constituents adhere coincides with the place at which the heat is supplied. Proceeding from this knowledge in accordance with the present invention, the coking process is carried into practice in the following manner: The heat is supplied to the contents of the boiler at its lowest part only until the production of the first distillate, but during the rest of the distillation process it is supplied at places which are less exposed to the deposit of solid constituents than the bottom of the still. In accordance with the invention this object is attained by replacing the stills hitherto generally employed by stills comprising either internal heating or employing flame tubes within the still or both means in conjunction. The stills are combined with heating plants which render it possible at the commencing of the distillation process and in the course thereof to expose different parts of the boiler to the most vigorous heating and which, even during the course of the operation, permit of modifying the conduction of the furnace gases. With such an arrangement the greater portion of the solid constituents can be deposited as coke on the bottom of the still, this part being exposed hereafter to a less degree of heat. Only a small layer of solid constituents becomes deposited on the flame tubes which are exposed to the greatest heating during the course of the operation and this entails relatively unimportant loss of heat. Owing to this arrangement it is possible to carry out the distillation to coke, with temperatures of the heating surfaces at which the iron becomes incandescent, only

to so small an extent that burning of the flame tubes exposed to the direct action of the furnaces, is almost entirely avoided. By this means the cost of upkeep of such an installation is largely reduced as compared with the cost hitherto made necessary because the necessary repairs are restricted almost entirely to the infrequent replacement of the flame tubes which can be effected without dismounting the boiler provided the masonry is suitably constructed.

In Figs. 1 to 4, of the accompanying drawings a boiler installation intended for distillation purposes and embodying the invention, is illustrated in two vertical sections at right angles to each other and in two horizontal sections on the lines A B and C D, of Fig. 1. Fig. 5 illustrates a special method of mounting the flame tubes.

As shown in this construction the usual cylindrical distillation still is replaced by a still *m*, provided with transverse flame tubes *n*. The intervals between the flame tubes *n* and between these tubes and the bottom of the boiler, are selected in such a manner that the coke becoming deposited on the lower parts of the flame tubes and on the boiler bottom can readily be removed. It should be noted that as a general rule the flame tubes *n*, must be located at such a height above the bottom and be made of such a size that even in the last phases of the process, only their lowest portions are embedded in the coke while the upper portions of the tubes *n*, remain free from coke and thus constitute heating members even at the completion of the process.

The boiler is preferably operated by means of two furnaces I and II. By means of the first furnace arranged immediately beneath the boiler *m* the distillation process is started by causing the furnace gases to flow directly against the bottom of the boiler and then through the flues 1, 2, 3, 4, of which 2 and 4 almost completely surround the walls of the still. The gases then pass to the chimney *a*. The second furnace II, with which the flame tubes *n*, *n*, the flue *o* extending downward beneath the bottom of the boiler, and the said flues 1, 2, 3 and 4 connect is started at or after the commencement of the distillation process and is maintained operative during this process. It is obvious that the form and number of the flame tubes *n*, can be increased according to requirements, or they may be replaced by a single flame tube. As already stated, it is also possible to arrange the furnace II, as

an internal furnace that is to say, to arrange it in the flame tubes.

Instead of the installation comprising two furnaces as in the embodiment of the invention described above, a single furnace can be employed but in this case it must be arranged in such a manner that by the provision of suitable registers the furnace draft can be directed so that at the beginning of the process it is the bottom of the boiler that is mainly heated while in the course of the process or operation the heat is chiefly supplied to the flame tubes. The essence of the method of heating to be obtained by the arrangement of the flame tubes therefore resides in the fact that on starting the distillation process, the furnace heat should be conducted directly onto the bottom of the still while during the further progress of the process it is conducted directly onto the flame tubes, the remaining surface of the still being heated throughout the entire duration of the distillation process by the hot gases passing to the chimney. In all cases it is advisable to arrange the heating installation in such a manner that the flame tubes can be removed without dismounting the boiler, or essential portions of the masonry.

Fig. 5 of the drawing shows a special method of mounting the flame tubes *n*, in which instead of mounting them directly on the wall of the boiler *m*, they are mounted in special sockets *t*. When the flame tubes *n* require renewal owing to their having been burnt through, this can be effected through the man-hole *h*.

What I claim and desire to secure, is—

Means for carrying into effect the coking process in the petroleum industry, comprising a still, a primary furnace in front of the lower part of the still, a second furnace beneath said still, individual grates for each of said furnaces and a grate for both furnaces combined, heat flues from one of said furnaces passing along the bottom of the still and surrounding the boiler walls, heat flues from the second furnace comprising the flame tubes and the remainder of the heating surfaces, the bottom of the still and its higher portions adapted to be heated together or the higher portions be heated alone at will.

In testimony whereof I affix my signature in the presence of two witnesses.

JOSEF WEISER.
